RIGID GRASS CATCHER

James V. Young, St. Louis, Mo., assignor to The
Perfection Manufacturing Company

Filed Apr. 16, 1975, Ser. No. 568,670

Term of patent 14 years

U.S. CL. D15—17   Int. CL. D15—03

FIG. 1.

FIG. 2.

FIG. 3.

FIG. 1 is a perspective view of a rigid grass catcher, showing the front, right side and top of my new design;

FIG. 2 is a perspective view showing the rear, left side and top thereof; and

FIG. 3 is a perspective view showing the front, right side and bottom thereof.

I claim:

The ornamental design for a rigid grass catcher, substantially as shown.
